(57) **CLAIM**

The ornamental design for a tangent integrated tilt sight, as shown and described.

DESCRIPTION

FIG. 1 is a perspective front view of the tangent integrated tilt sight in an open position, which embodies my design;

FIG. 2 is a perspective rear view of the tangent integrated tilt sight in an open position;

FIG. 3 is a perspective front view of the tangent integrated tilt sight in a closed position;

FIG. 4 is a perspective rear view of the tangent integrated tilt sight in a closed position;

FIG. 5 is a bottom view of the tangent integrated tilt sight;

FIG. 6 is a top side view of the tangent integrated tilt sight;

FIG. 7 is a front view of the tangent integrated tilt sight;

FIG. 8 is a rear view of the tangent integrated tilt sight;

FIG. 9 is left side view of the tangent integrated tilt sight; and,

FIG. 10 is a right side view of the tangent integrated tilt sight.
